STENCIL-PRINTING MACHINE

Samuel Rodman, Oakland, Calif., assignor to
Rodman Duplicator Corporation, a corpora-
tion of California

Application November 20, 1934, Serial No. 753,957

9 Claims. (Cl. 271—61)

My invention relates to improvements in stencil-printing machines and like rotary stencil-writing machines, and one of the objects thereof is the provision of means associated with the main shaft of the machine whereby the operation of the latter will cause said means to actuate for elevating the stock-supporting table, whereby the top sheet of the paper stock carried by the table will automatically be brought into proper position for operatively moving or feeding it to the printing drum at the desired moment relative to the rotation of the drum;

A further object is the provision of a pair of retaining fingers adapted to be engaged by the forward edge of the paper stock, and particularly the uppermost sheet of said stock, to prevent the same from moving forwards accidentally before the drum has been operatively rotated into proper position for receiving the paper, sheet by sheet;

A still further object is the provision of a transversely extending intermediate shaft having opposed end portion threaded for movably supporting the retaining fingers and their supporting blocks, whereby said fingers may be adjusted to the width of the paper stock carried by the stock-supporting table;

A still further object is the provision of a secondary shaft extending transversely of the machine and having a bevel gear at each end meshing with the bevel gears at the upper ends of a pair of vertically disposed threaded screws extending through and vertically movably supporting a pair of internally threaded lugs secured to the stock-supporting table, whereby the rotation of said secondary shaft in the proper direction will cause said screws to rotate and to move said lugs upwards or downwards, as the case may be, and to cause the stock-supporting table to move vertically in the same direction.

With the foregoing and still further objects and purposes in view which will appear as the description proceeds, my invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings—

Figure 1 is a side elevation of a stencil-printing machine embodying the present improvements.

Figure 2 is a view in elevation of the opposite

Figure 3 is a view of the feeder shoe and its associating parts, principally in section;

Figure 4 is a view of the ratchet lever and ratchet wheel associated therewith, portions of the lever being broken away;

Figure 5 is a top view of the machine;

Figure 6 is a rear end view thereof;

Figure 7 is a plan view of the outer end portion of the ratchet lever and portions of parts associated therewith;

Figure 8 is a view of the intermediate shaft and slider blocks and retaining fingers carried thereby;

Figure 9 is a top view of a portion of one of the slider blocks and its retaining finger, and a fragmental portion of a sheet of paper;

Figure 10 is a view in elevation of a portion of one of the slider blocks and retaining finger, and a portion of the paper stock; and

Figure 11 is a view in perspective of the guide bar.

Referring to the drawings in detail, throughout which like reference characters designate like parts:

(To facilitate associating the following description with the drawings, the side of the machine presented to the reader in Fig. 2, is deemed the right-hand side thereof; the opposite side, the left-hand side; the end next to the right-hand side of the drawing sheet, the front or forward end; and the end next to the left-hand side of the sheet, the rear end of the machine.)

The machine proper, and in which it is in general common with mimeographs at present in general use, comprises a frame 1, supported by front and rear legs 2, a stencil-supporting drum 3, which is supported by a main shaft 4, rotatably supported by the frame 1 and operated by a crank handle 5. The usual transversely extending roller 6 is rotatably mounted on the frame 1 below the drum 3, with which it coacts for feeding the paper stock operatively therebetween.

The rear legs 2 are provided with inwardly projecting lugs 7 having vertical openings 8, and inwardly extending brackets 9 provided with openings 10 and 11.

In the openings 8 and 10 are rotatably mounted vertically extending threaded screws 12, provided at their upper ends with bevel gears 13, which are in mesh with bevel gears 14 fixedly secured to the opposed ends of a transversely extending secondary shaft 15 rotatably mounted in the openings 11 formed in the upper or free ends of the brackets 9.

50

55

On one end of the shaft 15, intermediate the gear 14 and the bracket 9, is fixedly secured a ratchet wheel 16, while at the opposite end of said shaft is removably secured a crank handle 17.

5 On the main shaft 4, adjacent the right-hand side of the machine, and intermediate the frame 1 and drum 3, is eccentrically fixedly mounted a cam or disk 18 to provide an eccentric bearing for one end of a reciprocating lever 19, the opposite end of said lever being bifurcated to form a pair of spaced members 20, which are adapted to straddle the ratchet wheel 16, and support a transversely disposed ratchet pin 21, which is operatively engageable with the teeth of said ratchet wheel for rotating the shaft 15.

10 22 designates the stock-supporting table, which is provided with, and supported by, a pair of supporting-lugs 23, through which the screws 12 project and by the rotation of which screws, in either 15 direction, said lugs and the table may be operatively raised or lowered, as desired, relative to the frame 1.

To the rear end of the table 22 is removably secured a rear stop 24, against which the paper stock carried by the table is intended to abut for holding it in proper position thereon preparatory to feeding it, sheet by sheet, between the drum and its coating roller 6.

15 The rear stop 24 is preferably formed and connected to the table 22 in such a manner as to be movable rearwards and forwards thereon, to conform to the various dimensions of the paper stocks that may be carried on the table.

20 A transversely extending guide bar 25, having its upper edge formed into an upwardly projecting guide rib 26, is secured to opposite sides of the frame 1 by means of fastening pins 27.

25 To opposite sides of the frame 1, forwardly of the bar 25 and in parallelism therewith, is rotatably secured an intermediate shaft 28, which is provided adjacent its ends with right and left threaded portions 29, which portions project through the internally threaded openings 30 in guide blocks 31, which supports upwardly projecting outwardly inclined retarding fingers 32.

30 The guide blocks 31, which are adapted to be moved transversely towards and away from each other by the rotation of the shaft 28 to correspond to the width of the paper stock carried by the table 22, have grooves 33 formed in their lower sides, which grooves slidably receive the rib 26 and are thereby prevented from rotating about the axis of the shaft 28 during the rotation of the latter.

35 55 To the end of the main shaft 4, on the left-hand side of the machine, is fixedly secured an arm 34, to the free end of which is pivotally secured one end of a connecting link 35, the opposite end of which link being pivotally secured to the upper end of a rocker-arm 36, which has its lower end pivotally secured to the frame 1, by means of securing pins 37.

60 To the rocker-arm 36, intermediate its upper and lower ends, is secured, preferably fixedly, one end of a transversely disposed rocker-rod 38, the opposite end of which being secured, preferably fixedly, to the upper end of a complementary rocker-arm 39, pivoted at its lower end to the frame 1 by means of a fastening pin 40.

65 70 A feeder-shoe 41, which comprises a frame element embodying a pair of side members 42, a pair of tie-pins 43 for holding said side members in fixed spaced relation, and a flexible cushion element 44 removably secured to said side members 42 by means of a bolt 45 projecting through

75 said cushion element and between said side members and tie-pins and secured by means of a nut 46 and seating plate 47 seated on said tie-pins, is pivotally secured to the mid-portion of the rocker-rod 38 by means of openings 48 in one end of the side members 42 through which the rocker-rod movably projects. The feeder-shoe 41 is freely swingable on the rocker-rod 38 but is limited in its movement longitudinally of the rocker-rod by means of a collar 49 fixedly but movably secured to said rocker-rod between said side members 42, by means of a set-screw 42'.

80 While I prefer to form the cushion element 44 of rubber, rubber sponge, or similar material, it may, if so preferred, be formed of any other material or substance found suitable and appropriate.

85 The guide blocks 31, together with their retarding fingers 32, are adapted to function as the forward stops, and the rear stop 24 as the rear end stop, between which the paper stock carried by the table 22 is intended to be disposed preparatory to operatively feeding it, sheet by sheet, from the top thereof, to the drum 3 and roller 6. The rear end stop 24 is preferably movable forwards and rearwards, as may be required, relative to the table 22, to conform to the dimensions of said stock, so that the latter may be caused to fit snugly, but not too tightly, between said front and rear stops.

90 The retarding fingers 32, particularly the upper or free end portions thereof, are adapted to also function as means for temporarily holding the forward edge of the uppermost sheet of the paper stock from moving forward immediately upon the forward movement of the mid or intermediate portion thereof when engaged by the feeder-shoe 41. Such forward movement of said mid or intermediate portion of the sheet, will cause portions of the sheet, rearward of said fingers, to bulge slightly upwards, freeing it from the next sheet below and thereby permitting it to freely move forwards at the proper and pre-arranged time without carrying said next sheet accidentally along with it. Such temporary retention of the front edge of the sheet does not interfere with the full forward movement of the sheet, during the operation of the machine, for proper registration with the characters cut in the stencil carried by the drum 3, as the retention of said front edge of the sheet is only temporary and does not retard the prearranged and properly timed movement of the main body of the sheet.

95 The extent of engagement of said upper or free end portion of the fingers 32 with the top sheet of the paper stock, is regulatable by the movement of the guide blocks 31 along on the intermediate shaft 28 by rotating the latter in the required direction.

100 A sheet metal shield 50, preferably semi-circular in cross section, is disposed transversely of the machine over portions of the secondary shaft 15 and the bevel gears 13 and 14. A slot 51 is formed in the upper side of the shield to permit the members 20 of the arm 19 to freely move therebetween and the ratchet pin 21 to operatively engage and rotate the ratchet wheel 16.

105 A lever 52, which is pivoted at one end to the shield 50, is swingable across the slot 51, thereby permitting the free end of the arm 19 to be raised out of engagement with the ratchet wheel 16 and be temporarily supported thereon, thereby permitting the drum and its associated parts to be operated without rotating the shaft 15 and screws 75

12 for elevating the table 22, as well as permitting the said shaft 15 to be rotated by means of the crank-handle 17, for turning the screws 12 and elevating or lowering the table, independently of 5 the rotation of the drum 3.

In order to prevent thickening of the drawing, the transversely extending guide-bar 25, guide-blocks 31 and retarding fingers 32, connecting link 35, rocker-arm 36, and the rocker-rod 38, 10 have been eliminated from Figs. 2 and 6 thereof.

The operation of the present improved stencil-printing machine may be described, as follows:

A properly arranged stack of superimposed paper stock 53 intended to be stencil printed, is disposed on the table 22, with its forward end bearing lightly against the guide-blocks 31 and retarding fingers 32, after which the end stop 24 is secured to the table so as to bear lightly against the rear end of said stock. After confining the 20 paper between said guide-blocks and retarding fingers and the rear stop 24, against accidental fore and aft movement relative to the table, the free or bifurcated end of the reciprocating lever 19 is lifted free from engagement with the ratchet 25 wheel 16 and temporarily disposed on the lever 52 after swinging the latter from its normal position shown by the broken lines into the position indicated by the solid lines, in Fig. 7. The secondary shaft 15 is next rotated in the proper direction, 30 by means of the crank-handle 17, for rotating the screws 12 and elevating or lowering, as may be required, the table 22, until the top sheet of the stock 53 is disposed in the desired vertical alignment with the upper end portion of the retarding fingers 32 (see Figs. 9 and 10), after which the intermediate shaft 28 is rotated to move the guide-blocks 31 horizontally along thereon in the proper direction until the said upper end portions of the retarding fingers 32 are brought into 35 position for properly engaging the opposed forward corners of the uppermost sheet of said paper stock. After elevating or lowering the table 22, as above described, for properly aligning the paper with the retarding fingers 32, the feeder-shoe 41 40 is disposed in engagement with the upper surface of said paper, in the position thereon best illustrated in Figs. 2 and 5.

The machine is now ready, after first swinging the lever 52 out from under the free end of the reciprocating lever 19 and disposing the latter once more into operative engagement with the ratchet wheel 16, for printing, sheet after sheet, the paper comprising the paper stock carried by the table 22, which printing, including the feeding of the paper sheets to the drum 3, is automatically accomplished by simply rotating the crank-handle 5 in the proper direction (anti-clockwise), causing the drum 3 and the arm 34 to rotate in the same direction and in unison therewith; the rocker-arm 34 actuating the connecting link 35 and the rocker-arms 36 and 38, thereby causing the rocker-rod 37 to swing or oscillate forwards and backwards, defining a complete cycle of movement at each revolution of the said drum 3 55 and arm 34, and thereby causing the feeder-shoe 41, which has one end pivotally secured to said rocker-rod 37 and having its free end portion bearing on the paper stock 53, to move backwards and forwards on said stock in synchronism with the said forward and backward swinging or oscillation of said rocker-rod 37, and to engage and move the top sheet of said paper forward to be operatively engaged by the drum 3 and its coacting roller 6, in prearranged order of movement 60 with said drum and roller for receiving proper

contact with the printing characters in the printing stencil attached to said drum.

I claim:

1. In a stencil-printing machine of the character described, a frame, a guide-bar extending transversely of said frame and having its ends secured thereto, a guide-block associated with said guide-bar, and means for moving said guide-block slidably along on said guide-bar, said guide-block supporting a retarding finger. 10

2. In a stencil-printing machine of the character described, a frame, a guide-bar extending transversely of said frame and having its ends fixedly secured to opposite sides thereof, an intermediate shaft disposed in parallelism with said 15 guide-bar and having its ends rotatably supported by said frame, a pair of guide-blocks through which said intermediate shaft threadedly projects, said guide-blocks being movable relative to and in parallelism with said guide-bar by the rotation of said intermediate shaft, said guide-blocks supporting means adapted to be operatively engaged by the forwardly disposed edge of a sheet of paper and to temporarily retard it preparatory to feeding it to the printing drum of the 20 machine.

3. In a stencil-printing machine of the character described, a frame, an intermediate shaft having its ends rotatably supported by said frame and having opposed end portions threaded, means 30 disposed in parallelism with said shaft and supported by said frame, and a pair of retarding finger-supporting elements threadedly engaging said threaded portions whereby by rotation of said intermediate shaft said elements will be 35 caused to move in opposite directions longitudinally of said shaft, said means functionable for preventing rotation of said elements relative to said shaft.

4. In a stencil-printing machine of the character described, a frame, an intermediate shaft having its ends rotatably supported by said frame, a guide-block through which said shaft threadedly projects, and an upwardly projecting retarding finger having its lower end secured to 45 said guide-block, said retarding finger inclined in a vertical plane extending transversely of said frame.

5. In a stencil-printing machine of the character described, a frame, an intermediate shaft 50 having its ends rotatably supported by said frame, a guide-block through which said shaft threadedly projects, and an upwardly projecting retarding finger having its lower end supported by said guide-block, said retarding finger having its 55 upper end bent to one side relative to its intermediate body portion.

6. In a stencil-printing machine of the character described including a frame and a printing drum rotatably supported thereby, paper-retarding means supported by said frame, and means supported by said frame adapted for moving said paper-retarding means in either direction parallel to the axis of said drum. 60

7. In a stencil-printing machine of the character described having a frame portion rotatably supporting a printing drum, a guide bar having its opposed end portions supported by said frame, and paper-retarding means supported by said 65 guide bar and operably slidably along thereon in either direction in parallelism with the axis of said drum.

8. In a stencil-printing machine of the character described having a frame portion rotatably supporting a printing drum, in combination, a 70 75

- stock-supporting table vertically movably supported by said frame, paper-retarding means supported by said frame between said table and said drum, said paper-retarding means adapted to operatively contact and temporarily arrest the forward movement of a portion of the forward end portion of the uppermost sheet of said paper stock, and means supported by said frame manually operable for moving said paper-retarding means in either direction parallel to the axis of said drum independent of the rotation of said drum.
9. In a stencil-printing machine of the char-

acter described including a frame portion rotatably supporting a printing drum, a stock-supporting table vertically movably supported by said frame, and paper-retarding means supported by said frame and horizontally movable in either direction in a vertical plane parallel to the axis of said drum without changing the position thereof vertically, said table adapted for supporting paper stock, the path of travel of said paper stock from said table to said drum crossing said vertical plane. 5

SAMUEL RODMAN.
